CLAIM

The ornamental design for a stand for a wine aerator, as shown and described.

DESCRIPTION

FIG. 1 is a right side perspective view of a stand for a wine aerator.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines in the figures are included for illustrative purposes and form no part of the claimed design.
